UNITED STATES PATENT OFFICE.

WALTER G. KING, OF NEW YORK, N. Y.

DESIGN FOR A NOSE-GUARD.

44,534.

Specification for Design.

Patented Aug. 19, 1913.

Application filed March 22, 1912. Serial No. 685,589. Term of patent 14 years.

To all whom it may concern:

Be it known that I, WALTER G. KING, a citizen of the United States, residing at New York, in New York county and State of New York, have invented a new, original, and ornamental Design for Nose-Guards, of which the following is a specification, reference being made to the accompanying drawings, forming a part thereof.

Figure I represents a plan view of my improved design for nose guards, and Fig. II represents a side view thereof.

By reference to the drawings my improved design for a nose guard should be clearly understood, and it will be seen that

I have provided a new and ornamental guard comprising a pair of substantially parallel members arranged in staggered relation and connected by a suitable cross piece, one of said members having mounted thereon near one terminus thereof a concavo-convex pad.

I claim:

The ornamental design for a nose guard as shown and described.

WALTER G. KING.
